PLATING APPARATUS AND OPERATION
METHOD THEREOFCROSS-REFERENCE TO RELATED
APPLICATIONS

This application is a continuation-in-part application of U.S. patent application Ser. No. 16/656,863 entitled "PLATING APPARATUS AND OPERATION METHOD THEREOF", filed on Oct. 18, 2019, issued as U.S. Pat. No. 11,261,535 on Mar. 1, 2022, which claims the benefits of Singapore Patent Application No. 10201902611P, filed on Mar. 22, 2019 and Chinese Patent Application No. 201910391509.6, filed on May 10, 2019, the entire disclosure of which are incorporated herein by reference.

TECHNICAL FIELD

The present disclosure relates to a plating apparatus and a plating method thereof. In particular, the present disclosure relates to a cleaning module of the plating apparatus and a cleaning method for cleaning a sealing element of the plating apparatus.

BACKGROUND

Plating is a process in which a certain metal surface is plated with a thin layer of other metal or alloy using electrolysis principle. Since the introduction of plating technology, it has been widely used in different industrial fields. Starting from the early aesthetic-oriented decorative application, such as producing decorative and protective surface layers on mechanical products, the plating technology has gradually developed to be applied in high-tech industry at present, such as the chip package process. Plating technology has become an indispensable technology in the semiconductor microelectronic industry.

In general, the conventional plating technology typically provides a plating tank which accommodates a plating solution. In the plating process, a substrate to be plated is used as a cathode, and plated metal or other insoluble material is used as an anode; the cathode and the anode are placed in the plating tank; and direct current voltage is supplied between the two electrodes; and a surface of the substrate to be plated is reduced to form a coating due to the electrode reaction.

SUMMARY

The present disclosure provides a plating apparatus and an operation method thereof. The plating apparatus has a simple structure and convenient operation, which helps shortening the operation time of the substrate mounting process, improves the production efficiency of semiconductor package, and is particularly suitable for panel level semiconductor package.

A brief summary of the present disclosure is presented below to provide a basic understanding of some aspects of the present disclosure. The content of the present disclosure is not an extensive overview of the present disclosure and is not intended to identify key or critical elements of the present disclosure or the scope of the present disclosure. The following content of the present disclosure reveals some concepts of the present disclosure in a simplified form as a prelude to the specific embodiments provided below.

The present disclosure proposes plating apparatus for performing plating treatment on a substrate, comprising:

2

tank body comprising at least one side wall, the at least one side wall being provided with an opening extending from the inside to the outside of the tank body, the tank body being configured to accommodate a plating solution; and a fixing device configured to fix the substrate at the opening of the side wall.

According to various embodiments of the present disclosure, the fixing device is disposed at the outside of the tank body, so that the fixing device could be operated easily from the outside of the tank body.

According to various embodiments of the present disclosure, a substrate mounting plate fixed on an outer side of the side wall, wherein the substrate mounting plate is provided with a hole and a substrate mounting area arranged around the hole; and a position of the hole of the substrate mounting plate corresponds to a position of the opening of the side wall.

According to various embodiments of the present disclosure, the fixing device is disposed on the substrate mounting plate.

According to various embodiments of the present disclosure, the fixing device comprises two or more clamping pieces arranged on a periphery of the hole of the substrate mounting plate.

Thus, the fixing device can be constructed in a convenient and lightweight manner, and the substrate is fixed on the substrate mounting plate in a fluid seal manner.

At least one part of the clamping piece can move between an extended position and a retracted position at the retracted position of the clamping plate, the substrate can pass through the space above the substrate mounting area without hindrance, thereby allowing convenient operation of placing the substrate on the substrate mounting plate or removing the substrate from the substrate mounting plate.

According to an advantageous embodiment of the present disclosure, the at least one clamping piece comprises a plurality of clamping pieces; and the plurality of clamping pieces are arranged on a periphery of the hole of the substrate mounting plate.

According to a further advantageous embodiment of the present disclosure, the fixing device comprises a first driving mechanism and a second driving mechanism; the first driving mechanism is configured to drive at least a part of the clamping piece along a first direction, so that the at least a part of the clamping piece moves from the side of the substrate mounting area away from the hole to the substrate mounting area, the first direction is parallel to the substrate mounting plate and directed from the side of the substrate mounting area away from the hole to the substrate mounting area; and the second driving mechanism is configured to drive at least a part of the clamping piece along a second direction perpendicular to the substrate mounting plate, so that the at least a part of the clamping piece applies pressure towards the substrate mounting area.

The first driving mechanisms and the second driving mechanism of the plurality of clamping pieces can be connected to a control module, and the control module can respond to an instruction of the operator and simultaneously operate the plurality of clamping pieces. This automated implementation significantly reduces the fixed operation time and reduces the production cost. In addition, the fixing operation by the driving mechanisms is highly reproducible and uniform compared to the manual operation, thereby ensuring the reliability of the fixing operation and the sealing of substrate mounting.

According to various embodiments of the present disclosure, the clamping piece comprises a supporting plate and a

clamping plate, the supporting plate comprises a receiving slot; the clamping plate is inserted into the receiving slot and capable of sliding in the receiving slot along the first direction; the first driving mechanism is configured to drive the clamping plate along the first direction, so that the clamping plate extends out of the receiving slot and moves from the side of the substrate mounting area away from the hole to the substrate mounting area; and the second driving mechanism is configured to drive the clamping plate in the second direction, so that the clamping plate applies pressure towards the substrate mounting area.

According to various embodiments of the present disclosure, the clamping piece comprises a connecting plate disposed on the supporting plate and fixed to the first driving mechanism, the connecting plate comprises a cam slot extending in a direction between the first direction and the third direction to form an angle greater than 0° and less than 90° with the first direction, and a protrusion is fixed on the clamping plate and passes through the supporting plate to cooperate with the cam slot; and wherein the first driving mechanism is configured to drive the connecting plate along a third direction which is parallel to the substrate mounting plate and perpendicular to the first direction, so that the protrusion moves in the cam slot along an extension direction of the cam slot, and the clamping plate slides in the receiving slot of the supporting plate along the first direction.

According to various embodiments of the present disclosure, the fixing device further comprises a pivotal shaft connected to a middle part of the supporting plate; the second driving mechanism is configured to drive an end portion of the supporting plate away from the hole in the first direction to move away from the substrate mounting plate along the second direction, so that the supporting plate rotates about the pivotal shaft, an end portion of the supporting plate close to the hole in the first direction moves towards the substrate mounting plate along the second direction, and the clamping plate applies the pressure towards the substrate mounting area.

According to various embodiments of the present disclosure, the clamping plate comprises a cantilever element and a clamping end, the cantilever element is configured to be inserted into the receiving slot of the supporting plate; and the clamping end extends from an end of the cantilever element towards the substrate mounting plate and is configured to apply the pressure towards the substrate mounting plate; and in a case that the supporting plate is parallel to the substrate mounting plate, a first distance between the pivotal shaft and the second driving mechanism measured in the first direction is greater than a second distance between the pivotal shaft and the clamping plate measured in the first direction.

According to various embodiments of the present disclosure, the first distance is twice the second distance.

According to various embodiments of the present disclosure, a guide rail extending along the third direction is disposed on the supporting plate and configured to guide the connecting plate to move on the supporting plate along the third direction.

According to various embodiments of the present disclosure, the tank body comprises a plurality of side walls; and the opening is disposed on at least two of the plurality of side walls. Thus, plating treatment on a plurality of substrates to be plated can be performed simultaneously, thereby obtaining several-times the efficiency of plating treatment.

According to various embodiments of the present disclosure, the plating apparatus further comprises a substrate

stopper which is configured to move from the outside of the opening to a middle part of the opening.

The substrate stopper can comprise a supporting stand connected to the substrate mounting plate and an arm 5 roughly parallel to the substrate mounting plate. The arm can rotate between an idle position outside of the opening and a stop position above the opening in the plane parallel to the substrate mounting plate. Before plating treatment, the arm can be disposed at the idle position. In this case, the stop portion 10 is disposed on the outer side of the opening of the side wall, so as to mount and fix the substrate on the substrate mounting plate. During plating treatment, the arm can be rotated to the stop position. In this case, the stop portion 15 is disposed in the middle part of the opening of the side wall and stops on the outer side of the substrate to prevent the deformation of the substrate under the pressure of the plating solution in the tank body.

According to an advantageous embodiment of the present disclosure, the plating apparatus further comprises a plating 20 solution drive device disposed in the tank body and facing the opening, and the plating solution drive device is configured to drive the plating solution to flow towards the opening.

Thus, the plating solution near the substrate can be rapidly 25 replenished; the parameters such as temperature, concentration, pH and the like of the plating solution in the vicinity of the substrate remains constant; and the chemical composition of the plating solution uniformly dispersed. Therefore, the coating deposited on the substrate can be formed in 30 uniform thickness to improve the yield of plating treatment and reduce the production cost.

According to various embodiments of the present disclosure, the plating solution drive device is mounted on the side wall provided with the opening. Due to this configuration, 35 the movement process of the plating solution drive device can be implemented in a more stable manner, and the distance from the plating solution drive device to the substrate to be plated can be accurately controlled.

According to various embodiments of the present disclosure, 40 a distance between the plating solution drive device and the side wall provided with the opening is in a range from 2 mm to 4 mm. The placement of the plating solution drive device close to the side wall provided with the opening allows obtaining a coating with more uniform thickness.

According to various embodiments of the present disclosure, 45 the plating solution drive device comprises a plurality of blades arranged and configured to move in a plane parallel to the side wall provided with the opening.

According to various embodiments of the present disclosure, 50 the plating solution drive device comprises a plurality of nozzles arranged in an array and configured to move in a plane parallel to the side wall provided with the opening, and the plurality of nozzles are further configured to spray the plating solution towards the side wall provided with the opening.

According to another embodiment of the present disclosure, 55 a distance between adjacent nozzles is in a range from 1 mm to 5 mm; and the nozzle has a bore diameter in a range from 0.5 mm to 1 mm.

According to various embodiments of the present disclosure, 60 the plating apparatus further comprises at least one sealing element disposed in at least one of the following areas: an area of the substrate mounting plate around the hole or an area of the side wall, provided with the opening, around the opening.

According to various embodiments of the present disclosure, 65 a position at which the clamping end applies the

pressure towards the substrate mounting plate at least partially overlaps with a position of the sealing element in the direction perpendicular to the substrate mounting plate. Thus, the sealing effect of the sealing element may be improved due to the pressure applied to the sealing element, thereby preventing the leakage of the plating solution in the plating process.

According to various embodiments of the present disclosure, the clamping plate comprises a plurality of clamping ends, and positions at which the plurality of clamping ends apply pressure towards the substrate mounting plate are at least partially overlapped with the position of the sealing element in the direction perpendicular to the substrate mounting plate. Thus, the sealing effect of the sealing element may be further improved.

According to various embodiments of the present disclosure, the substrate mounting area is provided with electrical contacts configured to be electrically connected with the substrate.

According to various embodiments of the present disclosure, the electrical contacts are distributed on two opposite sides or four sides of the hole of the substrate mounting plate.

According to various embodiments of the present disclosure, a number of the electrical contacts distributed on each side of the hole is four or more.

According to an advantageous embodiment of the present disclosure, the plating apparatus further comprises a resistance measuring device electrically connected to the electrical contacts of the substrate mounting area.

After the substrate is mounted on the substrate mounting plate by utilization of the fixing device, the resistance measuring device may be utilized to measure the contact resistance between the substrate and the electrical contact, so as to determine whether the connection status between the substrate and the electrical contact is good. For instance, the resistance measuring device is electrically connected to four electrical contacts disposed on one side. Thus, the resistance measuring device may measure the contact resistance between the substrate and the electrical contacts by utilization of the four-point method.

According to various embodiments of the present disclosure, the plating apparatus further comprises an anode disposed in the tank body.

According to various embodiments of the present disclosure, the plating apparatus further comprises a power supply device respectively electrically connected with the anode and the electrical contacts.

According to various embodiments, the plating apparatus further comprises a cleaning module for cleaning the sealing element. The cleaning module may comprise a plate assembly coupled to the plating apparatus; and a roller assembly coupled to the plate assembly for cleaning the sealing element at a working location, wherein the roller assembly is configured to supply a fresh tape to the sealing element and configured to receive a contaminated tape from the sealing element, wherein the fresh tape is turned into the contaminated tape after cleaning the sealing element.

According to various embodiments, the roller assembly comprises a feeder roller configured to supply the fresh tape to the sealing element and a receiver roller configured to receive the contaminated tape from the sealing element.

According to various embodiments, the roller assembly further comprises a tension roller either before or after the sealing element for creating an internal tension to the fresh tape or the contaminated tape moving in the roller assembly.

According to various embodiments, the roller assembly further comprises a first idle roller after the feeder roller for directing the fresh tape from the feeder roller to the sealing element and a second idle roller after the sealing element for directing the contaminated tape from the sealing element to the receiver roller.

According to various embodiments, the plate assembly comprises two side plates and a base plate connecting the two side plates, wherein the feeder roller and the receiver roller of the roller assembly are configured to be rotatably coupled to the two side plates of the plate assembly.

According to various embodiments, the cleaning module further comprises a handling assembly for moving the roller assembly towards a working location where the roller assembly cleans the sealing element and for moving the roller assembly away from the working location after cleaning the sealing element.

According to various embodiments, the handling assembly comprises a first guiding rail extending in a first direction substantially parallel with an edge of the opening of the side wall and a handle movably coupled to the first guiding rail for moving the roller assembly along the first guiding rail in the first direction. The term "substantially" means the first direction shall be parallel sufficiently with the edge of the opening such that the movement of the roller assembly can be precisely controlled in the first direction.

According to various embodiments, the handling mechanism further comprises a second guiding rail extending in a second direction substantially perpendicular to a plane of the substrate mounting plate coupled to the side wall, and the handle is movably coupled to the second guiding rail for moving the roller assembly along the second guiding rail in the second direction. The term "substantially" means the second direction shall be perpendicular sufficiently with the plane of the substrate mounting plate such that the movement of the roller assembly can be precisely controlled in the second direction. Therefore, the handler can bring the roller assembly to every portion of the sealing element at or adjacent to the edge of the opening by precisely controlling the movement of the roller assembly in the first direction and the second direction.

According to various embodiments, the cleaning module further comprises a first linear actuator and a second linear actuator for driving the roller assembly to move along the first guiding rail and the second guiding rail, respectively.

According to various embodiments, the cleaning module further comprises a holding station for holding the roller assembly at a waiting location away from the working location, and the holding station comprises a securing mechanism for removably securing the roller assembly at the holding station.

According to various embodiments, the securing mechanism comprises a cylinder coupled to the plating apparatus and a locker coupled to the cylinder for removably locking the roller assembly at the holding station, wherein the locker is activated by the cylinder to lock the roller assembly.

The present disclosure further proposes an operation method of the abovementioned plating apparatus, comprising: placing the substrate on the outer side of the side wall and at the position of the opening, and operating the fixing device to fix the substrate; and performing plating treatment on the substrate.

According to various embodiments of the present disclosure, placing the substrate on an outer side of the side wall and at a position of the opening, and operating the fixing device to fix the substrate; and performing plating treatment on the substrate.

According to various embodiments of the present disclosure, placing the substrate on the opening of the side wall and operating the fixing device to fix the substrate comprises: measuring by the resistance measuring device a contact resistance between the substrate and the electrical contacts, and determining a connection status of the substrate and the electrical contacts.

According to various embodiments of the present disclosure, performing plating treatment on the substrate comprises: injecting the plating solution into the tank body, so that the plating solution contact with at least a part of the substrate; and performing plating treatment on the substrate by applying cathode voltage to the substrate through the electrical contacts and applying anode voltage to the anode.

According to various embodiments of the present disclosure, performing plating treatment on the substrate comprises: driving the plating solution to flow towards the substrate by using the plating drive device.

According to various embodiments, the present disclosure further provides a cleaning method for cleaning the sealing element of the plating apparatus with a cleaning module according to any one or a combination of embodiments of the abovementioned cleaning module after the operation method of the plating apparatus, comprising: positioning the roller assembly of the cleaning module at the working location; cleaning the sealing element with the fresh tape provided from the roller assembly; and positioning the roller assembly away from the working location.

According to various embodiments, the step of providing the fresh tape of the cleaning method further comprises: supplying the fresh tape from the feeder roller of the roller assembly; directing the fresh tape to the sealing element by the first idle roller of the roller assembly; directing the contaminated tape to the receiver roller after the sealing element by the second idle roller of the roller assembly; and receiving the contaminated tape into the receiver roller of the roller assembly.

According to various embodiments, the step of providing the fresh tape of the cleaning method further comprises: creating a first internal tension to the fresh tape by a first tension roller located after the feeder roller and before the sealing element; and creating a second internal tension to the contaminated tape with a second tension roller located after the sealing element and before the receiver roller.

According to various embodiments, the step of positioning the roller assembly of the cleaning module at the working location of the cleaning method comprises: moving the roller assembly from the waiting location to the working location along the first guiding rail and the second guiding rail, wherein the first guiding rail is substantially perpendicular to the second guiding rail.

BRIEF DESCRIPTION OF THE DRAWINGS

FIG. 1 illustrates an overall schematic diagram of a plating apparatus provided by various embodiments of the present disclosure, in which the plating apparatus is in the operating state, and a substrate is mounted on an opening of a side wall of a tank body through a fixing device;

FIG. 2 illustrates a perspective view of a tank body in various embodiments of the present disclosure;

FIG. 3 illustrates a sectional view of the plating apparatus as illustrated in FIG. 1 along the A-A line;

FIG. 4 illustrates a schematic diagram of a substrate mounting plate in various embodiments of the present disclosure;

FIG. 5 illustrates an overall schematic diagram of a plating apparatus in various embodiments of the present disclosure, in which the plating apparatus is in the non-operating state;

5 FIG. 6 illustrates a top view perspective diagram of a fixing device in various embodiments of the present disclosure, in which one clamping piece is illustrated;

10 FIG. 7 illustrates a front view schematic diagram of the fixing device in various embodiments of the present disclosure, in which one clamping piece is illustrated;

15 FIG. 8 illustrates a bottom view perspective diagram of the fixing device in various embodiments of the present disclosure, in which one clamping piece is illustrated;

FIG. 9 illustrates a sectional view of the fixing device as illustrated in FIG. 8 along the B-B line;

15 FIG. 10 illustrates a front view schematic diagram of the fixing device in various embodiments of the present disclosure, in which a substrate mounting plate and a substrate are illustrated;

20 FIG. 11 illustrates a partial enlarged view of a clamping end as illustrated in FIG. 10;

FIG. 12 illustrates a front view schematic diagram of a fixing device in another embodiment of the present disclosure;

25 FIG. 14 illustrates a schematic diagram of a plating solution drive device in various embodiments of the present disclosure;

FIG. 13 illustrates a schematic diagram of a plating solution drive device in another embodiment of the present disclosure;

30 FIG. 15 illustrates a schematic diagram of a plating solution drive device mounted to a side wall in various embodiments of the present disclosure;

FIG. 16 illustrates a schematic diagram of an operation 35 method of the plating apparatus, provided by various embodiments of the present disclosure;

FIG. 17 illustrates a perspective view of a cleaning module of the plating apparatus in various embodiments of the present disclosure;

40 FIG. 18 illustrates a perspective view of a roller assembly of the cleaning module in FIG. 17 at a waiting location;

DETAILED DESCRIPTION

The accompanying drawings are referred to in the following description of the exemplary embodiments of the present disclosure. The accompanying drawings form one part of the present disclosure. Various exemplary devices, systems, and environments in which various aspects of the present disclosure may be practiced are shown by way of illustration.

In the description of the disclosure, the orientation or positional relationship indicated by "horizontal", "vertical", "upper", "lower", "top", "bottom", "left", "right", "front", "rear" and the like is based on the orientation or positional relationship as illustrated in the accompanying drawings, or the orientation or positional relationship that is conventionally placed when the device set in the present disclosure is used, or the orientation or positional relationship that is conventionally understood by those skilled in the art, is merely for ease of description of the present disclosure and simplified description, which does not indicate or imply that the device or component referred to must have a particular orientation and is constructed and operated in a particular orientation, and thus is not to be construed as a limitation to the present disclosure.

In some plating techniques, a substrate to be plated is placed horizontally in a plating tank with a surface to be plated facing downward, and a plating solution is spouted from below towards the surface to be plated. This method is generally called spouting method, and has obvious defect that bubbles may be easily accumulated on the surface to be plated in the plating process and are difficult to be removed and may adversely affect the plating quality.

In other plating techniques, the plating solution is injected from a lower part of the plating tank and filled into a tank body, and the substrate to be plated is placed vertically in the plating tank and immersed into the plating solution. This method may be referred to as dipping method. In this case, although the bubbles may be easily removed to form a plating surface with high quality, overcoming the disadvantages of the spray method to some extent, however, it is necessary to provide a holding device for the substrate in order to vertically fix the substrate to be plated in the plating

tank. Such a holding device is generally complicated in structure, inconvenient to be operated, and difficult to firmly fix the substrate.

FIG. 1 is a schematic diagram of a plating apparatus provided by various embodiments of the present disclosure. FIG. 2 is a schematic diagram of a tank body 1 of the plating apparatus provided by the present disclosure. As illustrated in FIGS. 1 and 2, the plating apparatus comprises a tank body 1 (as illustrated in FIG. 1 by dotted lines) and a fixing device 2. The tank body 1 is, for instance, made from an insulating material and comprises a bottom wall B (FIG. 2) and a plurality of side walls S. An opening 15 for communicating the inside and the outside of the tank body 1 (e.g., extending from the inside to the outside of the tank body) is formed on at least one of the plurality of side walls S. The fixing device 2 is disposed on the outside of the tank body 1 and configured to fix a substrate 3 on an outer side of the side wall S and at the position of the opening 15. Thus, the opening 15 allows a surface to be plated of the substrate 3 to face the inside of the tank body 1 and to be in contact with a plating solution accommodated in the tank body 1.

The plating tank in the present disclosure can have the following advantages:

1. As the substrate is fixed on the opening of the side wall along the vertical direction, bubbles generated in the plating process can rise to an upper surface of the plating solution due to buoyancy, and no bubble will be accumulated on the surface to be plated, thereby avoiding adversely affecting the quality of the coating.
2. As the substrate is directly mounted on the outer side of the side wall of the tank body, compared with the case that the substrate is vertically fixed inside the plating tank, a substrate holding device with complex structure can be omitted, thereby simplifying the structure of the plating apparatus. In addition, the assembly and disassembly operations of the substrate can also be carried out in a simpler and faster way from the outside of the tank body.
3. Since the structure of the plating apparatus and the mounting operation of the substrate are greatly simplified, the plating tank in the present disclosure is particularly suitable for processing a large substrate, e.g., a substrate with a size of 600 mm, and thus is particularly suitable for large-sized panel level semiconductor package.

As illustrated in FIG. 2, the plurality of side walls S of the tank body 1 comprise a front wall 11, a rear wall 12, a left wall 13 and a right wall 14. The bottom wall B and the plurality of side walls S define an accommodating space suitable for accommodating the plating solution together. The plating apparatus can further comprise a plating solution pumping device (not illustrated). FIG. 2 only illustrates an example of a tank body provided with four side walls. However, the embodiment of the present disclosure is not limited thereto. For instance, the tank body can comprise less than four side walls or more than four side walls. For instance, side wall parts positioned in the same plane are referred to as one side wall, and side wall parts positioned in different planes are referred to as different side walls.

According to various embodiments of the present disclosure, at least one of the side walls S of the tank body 1 is provided with an opening 15 for communicating the inside and the outside of the tank body 1 (e.g., extending from the inside to the outside of the tank body). The opening 15 can have a shape basically consistent with that of an area to be processed of the substrate 3, for instance, a roughly rectangular shape.

11

In some examples, at least two of the side walls S of the tank body 1 are provided with the opening 15 for communicating the inside and the outside of the tank body 1. In various embodiments of the present disclosure, the opening 15 for communicating the inside and the outside of the tank body 1 is formed on two opposite side walls S of the tank body 1, for instance, on the front wall 11 and the rear wall 12 as illustrated in FIGS. 1 and 2. In FIG. 2, the opening on the rear wall 12 is invisible.

The inside of the tank body 1 can further comprise partition walls. The partition walls and the side walls S of the tank body 1 define a plurality of separate plating tank parts in the tank body 1. Each plating tank part can correspond to one of the at least two side walls S provided with the openings 15. In the embodiment as illustrated in FIG. 2, a first partition wall 16a and a second partition wall 16b extend between the left wall 13 and the right wall 14 in a direction parallel to the front wall 11 and the rear wall 12 provided with the openings 15, so as to define two separate plating tank parts in the tank body 1. A first plating tank part is defined by the front wall 11, the left wall 13, the right wall 14, the first partition wall 16a and the bottom wall B, and a second plating part is defined by the rear wall 12, the left wall 13, the right wall 14, the second partition wall 16b and the bottom wall B.

FIG. 3 is a sectional view of the plating apparatus as illustrated in FIG. 1 along the A-A line. As illustrated in FIG. 3, a first substrate 3a is fixed at the front wall 11 and in contact with the plating solution L accommodated in the first plating tank part. A second substrate 3b is fixed at the rear wall 12 and in contact with the plating solution L accommodated in the second plating tank part. The first plating tank part and the second plating tank part can be respectively provided with a plating solution inlet not illustrated in the figure) on the bottom wall B of the inside thereof. A plating solution outlet O can be disposed on the bottom wall B of the tank body 1 between the first partition wall 16a and the second partition wall 16b. That is to say, the plating solution outlet O is disposed outside the first plating tank part and the second plating tank part. The height of the first partition wall 16a and the second partition wall 16b can be less than that of the front wall 11 and the rear wall 12. In the plating process, the plating solution L is injected into the first plating tank part and the second plating tank part from the plating solution inlets in the first plating tank part and the second plating tank part and gradually filled into the first plating tank part and the second plating tank part. When the liquid level of the plating solution L arrives at the level of the first partition wall 16a and the second partition wall 16b, the plating solution L overflows from the first plating tank part and the second plating tank part (as illustrated by streamlines of the plating solution L schematically drawn in FIG. 3) and is discharged from the tank body 1 through the plating solution outlet O. Thus, the first plating tank part and the second plating tank part in the tank body 1 can be separated from each other and perform plating treatment on the first substrate 3a fixed on the front wall 11 and the second substrate 3b fixed on the rear wall 12 at the same time in a way that does not affect each other. Therefore, the processing efficiency of the plating apparatus can be greatly improved.

In some examples, the opening is disposed on more than two side walls of the tank body, and one or more openings can be disposed on each of the side walls. Discrete plating tank parts can be divided inside the tank body according to the number of the openings to simultaneously perform

12

plating treatment on more substrates to be plated, thereby improving the efficiency of plating treatment by several times.

As illustrated in FIG. 3, the plating apparatus further comprises an anode 4 which can be disposed in the plating tank and faces the side walls 11 and 12 provided with the openings. The anode 4 is, for instance, a plate member formed by plated metal. The plating apparatus can further comprise a power supply device 5. The power supply device 5 has an anode connected to the anode 4, and a cathode connected to the substrate to be plated 3. In the plating process, the power supply device 5 can apply voltage between the substrate to be plated 3 and the anode 4. Thus, electrons with negative charges will accumulate on the surface to be plated of the substrate 3 to be plated, while the plated metal of the anode 4 will precipitate metal ions with positive charges. The metal ions with positive charges are attracted by the negative charges carried by the electrons accumulated on the surface to be plated and flow to the surface to be plated, and combine with the electrons to form metal atoms, which are then deposited on the surface to be plated to form a plated metal layer.

As illustrated in FIG. 1, in some examples, the plating apparatus further comprises a substrate mounting plate 6. The substrate 3 is mounted on the substrate mounting plate 6 and fixed on the outer side of the side wall S of the tank body 1. For instance, the substrate mounting plate 6 is disposed between the fixing device 2 and the side wall S. An exemplary structure of the substrate mounting plate 6 will be described below with reference to FIGS. 4 and 5.

As illustrated in FIG. 4, the substrate mounting plate 6 is provided with a hole 65. The hole 65 can have a shape substantially consistent with that of the opening 15 of the side wall S or a region to be processed of the substrate 3. In the embodiment as illustrated in FIG. 4, the hole 56 of the substrate mounting plate 6 is of a roughly rectangular shape. The substrate mounting plate 6 is fixed on the outer side of the side wall S provided with the opening 15, so that the position of the hole 65 of the substrate mounting plate 6 can correspond to the position of the opening 15 of the side wall S (as illustrated in FIG. 5). For instance, the shape and the size of the hole 65 of the substrate mounting plate 6 are respectively the same as the shape and the size of the opening 15 of the side wall S, or the shape of the hole 65 of the substrate mounting plate 6 is the same as the shape of the opening 15 of the side wall S but the size of the hole is slightly larger or slightly smaller than the size of the opening of the side wall 5, but the embodiment of the present disclosure is not limited thereto. For instance, the phrasing that the position of the hole 65 of the substrate mounting plate 6 "corresponds to" the position of the opening 15 of the side wall S refers to that the areas of the hole 65 and the opening 15 are at least partially overlapped. In some examples, "corresponds to" refers to that the hole 65 and the opening 15 are in a state that the hole 65 and the opening 15 have a maximum overlapping area. In the plating process, the surface to be plated of the substrate 3 can be exposed in the plating solution in the tank body 1 through the hole 65 in the substrate mounting plate 6 and the opening 15 in the side wall S.

In some examples, the fixation between the substrate mounting plate 6 and the side wall S can be a detachable connection through one or more fasteners (for example, screws or bolts). In some examples, the fixation between the substrate mounting plate 6 and the side wall S can be almost permanent connection (e.g., welded joint or adhesive).

13

The substrate mounting plate 6 is provided with a substrate mounting area 6A (as illustrated by a dotted box part in FIG. 4). The substrate mounting area 6A is arranged around the hole 65 and configured to extend along each side of the hole 65. For instance, when the substrate 3 is mounted on the substrate mounting plate 6, the edge of the substrate 3 laps over the substrate mounting area 6A.

One or more electrical contacts 66 are disposed in the substrate mounting area 6A of the substrate mounting plate 6 and configured to be electrically connected with the substrate to be plated 3. The electrical contacts 66 are electrically connected to the cathode of the power supply device 5 (FIG. 3). Thus, when the substrate to be plated 3 is mounted on the substrate mounting plate 6, the electrical connection between the substrate to be plated 3 and the cathode is provided.

The electrical contacts 66 can be arranged along one or more sides of the hole 65 of the substrate mounting plate 6. In the embodiment as illustrated in FIG. 4, a plurality of electrical contacts 66 are equidistantly distributed on two opposite sides of the hole 65 of the substrate mounting plate 6. In other embodiments, the plurality of electrical contacts 66 can also be equidistantly distributed on four sides of the hole 65 of the substrate mounting plate 6. In various embodiments, four or more electrical contacts 66 are distributed on each side.

In some examples, the plating apparatus can further comprise a resistance measuring device (not illustrated) electrically connected to the above electrical contact 66. After the substrate 3 is mounted on the substrate mounting plate 6 by means of the fixing device 2, the resistance measuring device can be used to measure the contact resistance between the substrate 3 and the electrical contacts 66, so as to determine whether the connection status between the substrate 3 and the electrical contacts 66 is in good condition. For instance, the resistance measuring device is electrically connected to four electrical contacts 66 disposed on one side. Thus, the resistance measuring device can measure the contact resistance between the substrate 3 and the electrical contacts 66 by utilization of the four-point method. Traditional plating apparatuses cannot easily, measure the contact resistance for detecting any abnormalities in electrical connections during the plating treatment, which would cause defects or even failures to the plating, such as an uneven plating thickness. In contrast, the plating apparatus of the present invention provides a simple, convenient, and reliable way of measuring the contact resistance between the substrate 3 and the electrical contacts 66 during the plating treatment. In particular, the contact resistance can be measured in a real-time manner during operation of the plating apparatus for consistently, monitoring the plating treatment of the substrate 3. If the contact resistance increases abnormally, from a pre-determined value, the plating apparatus can be suspended or stopped from the operation to check the electrical connections between the power supply device 5 and the substrate 3. In this way, the area to be processed on the substrate 3 can be plated under precise control and an even plating thickness can be obtained accordingly.

According to various embodiments of the present disclosure, as illustrated in FIG. 1, the fixing device 2 is fixed on the substrate mounting plate 6 and configured to mount the substrate to be plated 3 on the substrate mounting area of the substrate mounting plate 6, for instance, by applying pressure to the substrate 3 in the substrate mounting area in the direction towards the side wall 3.

In other embodiments, the fixing device 2 can also be set in a way different from that of the embodiment as illustrated

14

in FIG. 1. Optionally, the fixing device 2 can be directly disposed on the side wall S of the tank body 1. Optionally, the fixing device 2 can be a pressure applying device completely independent of the tank body 1 and the substrate mounting plate 6.

According to various embodiments of the present disclosure, the fixing device 2 comprise at least one clamping piece. In some examples, the fixing device 2 can comprise a plurality of clamping pieces. As illustrated in FIGS. 1 and 10 to 5, four clamping pieces 20 are disposed on the periphery of the hole 65 of the substrate mounting plate 6 and are respectively distributed at positions close to four sides of the hole 65 of the substrate mounting plate 6. Each clamping piece 20 is configured to apply a pressure to the substrate 3 on a side of the hole 65 along the direction towards the side wall S. Thus, the fixing device can be constructed in a convenient and lightweight manner, and the substrate 3 is fixed on the substrate mounting plate 6 in a fluid seal manner.

20 An exemplary structure of the clamping piece 20 in various embodiments of the present disclosure will be described below with reference to FIGS. 6 to 10. In the following description, the xyz coordinate system is defined with reference to the substrate mounting plate 6. The z axis is perpendicular to the substrate mounting plate 6, and a positive direction thereof is the direction away from the substrate mounting plate 6. The x axis is perpendicular to the side of the hole 65 of the substrate mounting plate 6, and a positive direction thereof is directed from one side of the substrate mounting area 6A away from the hole 65 to the substrate mounting area 6A, namely directing from the substrate mounting area OA to the center of the hole 65.

According to various embodiments of the present disclosure, as illustrated in FIG. 6, the clamping piece 20 can 35 comprise a supporting plate 21 and a clamping plate 22.

The supporting plate 21 is a plate member extending along the length direction, the width direction, and the thickness direction. The length direction is parallel to the side of the hole 65 of the substrate mounting plate 6 close to the supporting plate 21. The width direction is perpendicular to the side of the hole 65 of the substrate mounting plate 6 close to the supporting plate 21.

As illustrated in FIG. 7, the clamping plate 22 is a plate member having an L-like sectional shape and comprises a 45 cantilever element 23 and a clamping end 24 which form two branches of the L-like shape. The clamping end 24 extends from one end of the cantilever element 23 along a direction roughly perpendicular to the extension direction of the cantilever element 23. The clamping end 24 is configured to contact the substrate 3 and apply a pressure to the substrate 3 in the direction towards the substrate mounting plate 6.

For the convenience of description, the geometric characteristics of the supporting plate 21 are defined as follows.

55 As illustrated in FIG. 6, the supporting plate 21 comprises an upper surface 211 and a lower surface 212, which are opposite to each other and extend in the length direction and the width direction. The lower surface 212 is a surface facing the substrate mounting plate 6, and the upper surface 211 is a surface facing away from the substrate mounting plate 6. The supporting plate 21 comprises an inner side surface 213 and an outer side surface 214, which are opposite to each other and extend in the length direction and the thickness direction. The inner side surface 213 faces the hole 65 of the substrate mounting plate 6, and the outer side surface 214 faces away from the hole 65 of the substrate mounting plate 6. The supporting plate 21 further comprises a front surface 215

15

and a rear surface 216, which are opposite to each other and extend in the width direction and the thickness direction. The front surface 215 is a surface near the bottom of the image in FIG. 6. The supporting plate 21 comprises two opposite end portions along the width direction which are respectively an inner end portion 217 and an outer end portion 218. The inner end portion 217 terminates at the inner side surface 213, and the outer end portion 218 terminates at the outer side surface 214.

The supporting plate 21 comprises a receiving slot 21s (as illustrated in FIGS. 8 and 9) which is open on the inner side surface 213. The cantilever element 23 of the clamping plate 22 is inserted into the receiving slot 21s through the opening on the inner side surface 213 of the supporting plate 21. The cantilever element 23 is configured to slide in the receiving slot 21s along the x-axis direction, so that the clamping plate 22 moves between an extension position (referring to FIG. 8) and a retraction position (referring to FIG. 9). The extension position is closer to the center of the hole 65 of the substrate mounting plate 6 along the x-axis direction compared with the retraction position. At the extension position, a part (for instance, the clamping end 24) of the clamping plate 22 can be positioned above the substrate mounting area 6A. At the retraction position, the clamping plate 22 is not positioned above the substrate mounting area 6A. The phrasing of "positioned above the substrate mounting area 6A" indicates that an orthographic projection on the substrate mounting plate 6 is overlapped with the substrate mounting area 6A. Therefore, at the retraction position of the clamping plate 22, the substrate 3 can pass through the space above the substrate mounting area 6A without hindrance, thereby allowing convenient operation of placing the substrate 3 on the substrate mounting plate 6 or removing the substrate 3 from the substrate mounting plate 6.

As illustrated in FIG. 6, the supporting plate 21 is configured to rotate about a pivotal axis P parallel to the y axis, so that the supporting plate 21 can move between an inclination position (as illustrated in FIG. 7) and a parallel position (as illustrated in FIG. 10), and then the clamping end 24 of the clamping plate 22 can move away from or close to the substrate mounting area 6A in the z-axis direction. As illustrated in FIG. 7, at the inclination position, the supporting plate 21 is inclined relative to the substrate mounting plate 6, namely an angle α of greater than 0° and less than 90° is formed between the upper surface 211 (or the lower surface 212) of the supporting plate 21 and the plane of the substrate mounting plate 6, so that the inner end portion 217 of the supporting plate 21 can be farther away from the substrate mounting plate 6 compared with the outer end portion 218. At the inclination position, the clamping end 24 of the clamping plate 22 does not contact the substrate 3 disposed on the substrate mounting plate 6. As illustrated in FIG. 10, at the parallel position, the supporting plate 21 is roughly parallel to the substrate mounting plate 6, and the clamping end 24 of the clamping plate 22 presses against the substrate 3 disposed on the substrate mounting plate 6.

The operation process of the fixing device 2 is as follows: in the case that the plating apparatus does not operate, the supporting plate 21 is at the inclination position and the clamping plate 22 is at the retraction position. The operator can place the substrate to be plated 3 on the substrate mounting area 6A of the substrate mounting plate 6. After the substrate is placed, the operator can move the clamping plate 22 disposed in the receiving slot 21s of the supporting plate 21 from the retraction position to the extension position, so that the clamping end 24 of the clamping plate 22

16

can move to the position above the substrate mounting area 6A. The operator can then move the supporting plate 21 from the inclination position to the parallel position, so that the clamping end 24 of the clamping plate 22 can move towards the substrate mounting area 6A and apply a pressure to the substrate 3, and the substrate 3 is therefore fastened on the substrate mounting plate 6 in the substrate mounting area 6A.

In a variant example not illustrated of the present disclosure, the clamping piece 20 can be a plate member in which a pressing portion is fixed at one end, and can move in the x-axis direction and the z-axis direction integrally under the guidance of, for example, a guide rail. In the process of mounting the substrate 3, the clamping piece 20 can move along a guide rail extending along the x-axis direction towards the center of the hole 65 at first, so that the pressing portion can be disposed above the substrate mounting area 6A. Different from the pivotal motion around the y axis of the supporting plate 21 in the above embodiment, in this embodiment, the clamping piece 20 can integrally perform a linear movement towards the substrate mounting plate 6 along a guide rail 28 (refer to FIG. 8) extending along the z-axis direction, so that the pressing portion can apply a pressure to the substrate 3 on the substrate mounting area 6A.

As for the design of the clamping piece 20, the principle followed by the present disclosure is that at least one part of the clamping piece 20 can move in the x-axis direction and the z-axis direction. Firstly, at least one part of the clamping piece 20 can move in the x-axis direction between one side of the substrate mounting area 6A away from the hole 65 (corresponding to the above retracted position) and the substrate mounting area 6A (corresponding to the above extended position), so as to leave an operation space for the placement and removal of the substrate 3 above the substrate mounting area 6A. Secondly, at least one part (for instance, the clamping end 24) of the clamping piece 20 can move in the z-axis direction, so as to press against the substrate 3 disposed on the substrate mounting plate 6 and apply a pressure to the substrate, or release the pressure and leave from the substrate 3. Under the guidance of this principle, other structural designs, and movement modes of the clamping piece 20 can be envisioned by those skilled in the art without departing from the scope of protection of the present disclosure.

According to various embodiments of the present disclosure, the fixing device 2 further comprises driving mechanisms which are configured to drive the motion of the clamping piece 20.

In some examples, the fixing device 2 comprises a first driving mechanism 71 and a second driving mechanism 72. The first driving mechanism 71 is configured to drive at least one part of the clamping piece 20 along the x-axis direction, so that the at least one part of the clamping piece 20 can move from one side of the substrate mounting area 6A away from the hole 65 to the substrate mounting area 6A. The second driving mechanism 72 is configured to drive at least one part of the clamping piece 20 along the z-axis direction, so that the at least one part of the clamping piece 20 can apply a pressure towards the substrate mounting area 6A.

It should be noted that "the first driving mechanism 71 drives at least one part of the clamping piece 20 along the x-axis direction" is not limited to the case where the movement trajectory of the at least one part of the clamping piece 20 is along the x-axis direction. The at least one part of the clamping piece 20 can also move along a direction that is at an angle to the x-axis direction driven by the first driving

mechanism 71. For instance, in a state where the clamping piece 20 is at, for example, the inclination position as illustrated in FIG. 7, the movement direction of the at least one part of the clamping piece 20 forms a certain angle with the x-axis direction. “The first driving mechanism 71 drives the at least one part of the clamping piece 20 along the x-axis direction” should be understood as that the motion of the at least one part of the clamping piece 20 contains a motion component along the x-axis direction.

The driving mechanism can be any of a variety of linear drive units known to those skilled in the art, e.g., an electric motor, a cylinder, or a ball screw. The first driving mechanisms 71 and the second driving mechanism 72 of the plurality of clamping pieces 20 can be connected to a control module, and the control module can simultaneously operate the plurality of clamping pieces 20 in response to an instruction of the operator. This automated implementation significantly reduces the fixed operation time and reduces the production cost. In addition, the fixing operation by the driving mechanisms is highly reproducible and uniform compared to manual operation, thereby ensuring the reliability of the fixing operation and the sealing effect of substrate mounting.

FIGS. 8-10 illustrate in detail the first driving mechanism 71 and the second driving mechanism 72 in various embodiments of the present disclosure. As an example, both the first driving mechanism 71 and the second driving mechanism 72 are in the form of a cylinder, and the cylinder can comprise a cylinder barrel and a piston rod capable of performing linear reciprocating motion in the cylinder barrel.

FIG. 8 is a bottom view perspective diagram of the fixing device 2 in the present disclosure (observed from the lower surface 212 of the supporting plate 21), FIG. 9 is another bottom view perspective diagram of the fixing device 2 in the present disclosure illustrated in a sectional form (observed from the lower surface 212 of the supporting plate 21). As shown in FIG. 8 and FIG. 9, the first driving mechanism 71 is located at the lower surface 212 of the supporting plate 21. The first driving mechanism 71 may have a bulky size; accordingly, the fixing device 2 need to have a large profile for accommodating the first driving mechanism 71, which may cause difficulties or inconvenience to fix the substrate 3 to the substrate mounting plate 6. Alternatively, the first driving mechanism 71 may be located outside the supporting plate 21 (not shown), which would reduce the profile of the fixing device 2 and thus facilitates to fix the substrate 3 to the substrate mounting plate 6.

The fixing device 2 can comprise two support members 26 respectively disposed at the front surface 215 and the rear surface 216 of the supporting plate 21. The first driving mechanism 71 is configured such that the cylinder barrel thereof is fixed at one of the support members 26 and the longitudinal axis of the cylinder barrel extends along the y-axis direction, so that the piston rod of the first driving mechanism 71 can perform linear reciprocating motion along the y-axis direction.

Apart from the supporting plate 21 and the clamping plate 22, the clamping piece 20 further comprises a connecting plate 27 which is disposed on the lower surface 212 of the supporting plate 21 and fixedly connected to an end portion of the piston rod of the first driving mechanism 71. The guide rail 28 extending along the y-axis direction can also be disposed on the lower surface 212 of the supporting plate 21. Thus, the linear motion along the y-axis direction of the connecting plate 27 can be guided along the guide rail 28.

The connecting plate comprises at least one cam slot 27c. The cam slot 27c is of an elongated shape, for instance, an oblong shape, and an extension axis thereof is between the x axis and the y axis and forms an angle of larger than 0° and smaller than 90° with the x axis (FIG. 9). In the embodiment as illustrated in FIG. 8, two cam slots 27c are provided.

As illustrated in FIGS. 8 and 9, the cantilever element 23 of the clamping plate 2 can be provided with a cylindrical protrusion 23p. The protrusion 23p passes through the supporting plate 21 and engages with the cam slot 27c of the connecting plate 27. Thus, the supporting plate 21 can be provided with a through hole 21h for the protrusion 23p to move freely therein (FIG. 9), and the through hole 21h communicates the receiving slot 21s of the supporting plate 21 and the lower surface 212 of the supporting plate 21 (e.g., extends from the receiving slot 21s of the supporting plate 21 to the lower surface 212 of the supporting plate 21). In the embodiment as illustrated in FIG. 8, two protrusions 23p are provided.

In the case that the connecting plate 27 performs linear motion along the y axis driven by the first driving mechanism 71, the connecting plate 27 drives the protrusion 23p to move in the cam slot 27c along the extension axis of the cam slot 27c, so that the clamping plate 22 can slide in the receiving slot 21s of the supporting plate 21 along the x-axis direction and thus move between the extension position and the retraction position.

FIG. 8 illustrates the clamping plate 22 disposed at the extension position, and FIG. 9 illustrates the clamping plate 22 disposed at the retracted position. Starting from the position as illustrated in FIG. 8, when the first driving mechanism 71 drives the connecting plate 27 to move towards the positive direction of the y axis, the protrusion 23p moves along the extension axis of the cam slot 27c from a position in the cam slot 27c closest to the center of the hole 65 to a position in the cam slot 27c farthest from the center of the hole 65, so that the clamping plate 22 can move to the retraction position as illustrated in FIG. 9. Reversely, starting from the position as illustrated in FIG. 9, when the first driving mechanism 71 drives the connecting plate 27 to move towards the negative direction of the y axis, the protrusion 23p moves along the extension axis of the cam slot 27c from the position in the cam slot 27c farthest from the center of the hole 65 to the position in the cam slot 27c closest to the center of the hole 65, so that the clamping plate 22 can move to the extension position as illustrated in FIG. 8.

As illustrated in FIG. 10, the second driving mechanism 72 is configured such that the cylinder barrel thereof is fixed on the substrate mounting plate 6 and the longitudinal axis of the cylinder barrel extends along the z axis direction, so that the piston rod of the second driving mechanism 72 can perform linear reciprocating motion along the z-axis direction. The outer end portion 218 of the supporting plate 21 is fixedly connected to the end portion of the piston rod of the second driving mechanism 72.

Returning to FIG. 8, the supporting plate 21 can comprise a pivotal shaft 29 protruding from the front surface 215 and the rear surface 216 thereof, so as to define a pivotal axis P. The support member 26 is provided with a mounting hole, and the pivotal shaft 29 of the supporting plate 21 can be inserted into the mounting hole of the support member 26. The mounting hole can also be provided with a bearing for supporting the rotating pivotal shaft 29 in the mounting hole. In some examples, the pivotal shaft is connected to the middle part of the supporting plate, and the middle part refers to the position between the inner end portion and the

outer end portion of the supporting plate. In some examples, the pivotal shaft 29 is disposed at a roughly middle position of the supporting plate 21 in the width direction.

In the case that the outer end portion 218 of the supporting plate 21 performs linear motion along the z axis driven by the second driving mechanism 72, the supporting plate 21 can rotate about the pivotal shaft 29, so that the supporting plate 21 can move between the parallel position and the inclination position.

In the embodiment as illustrated in FIG. 10, in a state where the supporting plate 21 is at the parallel position, as measured along the x-axis direction, the first distance L1 between the pivotal shaft 29 and the second driving mechanism 72 is greater than the second distance L2 between the pivotal shaft 29 and the clamping end 24 of the clamping plate 22. As observed in the xz plane, the pivotal axis P of the pivotal shaft 29 and the xz plane intersect at a supporting point P1, and the supporting point P1 is point of support of the lever motion of the clamping piece. The first distance L1 between the pivotal shaft 29 and the second driving mechanism 72 refers to the distance between the supporting point P1 and a longitudinal axis Q of the cylinder barrel of the second driving mechanism 72 along the x-axis direction. The second distance L2 between the pivotal shaft 29 and the clamping end 24 of the clamping plate 22 refers to the distance between the supporting point P1 and an extension axis R of the clamping end 24 of the clamping plate 22 along the x-axis direction.

Thus, the force applied by the second driving mechanism 72 can be amplified through the lever principle, so that the fixing of the substrate 3 at the clamping end 24 of the clamping plate 22 can be more stable, thereby enhancing the sealing effect and preventing the leakage of the plating solution during the plating process.

In some examples, the first distance L1 is twice the second distance L2.

FIG. 7 illustrates the fixing device 2 of which the supporting plate 21 is at the inclination position and the clamping plate 22 is at the extension position. FIG. 10 illustrates the fixing device 2 of which the supporting plate 21 is at the parallel position and the clamping plate 22 is at the extension position. Starting from the position as illustrated in FIG. 7, when the second driving mechanism 72 drives the outer end portion 218 of the supporting plate 21 along the positive direction of the z axis, the supporting plate 21 can rotate about the pivotal shaft 29 until arriving at the parallel position as illustrated in FIG. 10. During this process, the inner end portion 217 of the supporting plate 21 and the clamping end 24 of the clamping plate 22 roughly moves along the negative direction of the z axis. At the parallel position as illustrated in FIG. 10, the second driving mechanism 72 drives the outer end portion 218 of the supporting plate 21 along the positive direction of the z axis, so that the clamping end 24 of the clamping plate 22 can apply a pressure to the substrate 3 in the substrate mounting area 6A along the negative direction of the z axis. Thus, the substrate 3 is firmly mounted on the substrate mounting plate 6.

In some examples, the pivotal shaft 29 of the supporting plate 21 can be arranged in a manner different from that of the above embodiment. For instance, the pivotal shaft 29 can be disposed on the outer end portion 218 of the supporting plate 21 in the width direction, and the end portion of the piston rod of the second driving mechanism 72 is connected to the middle part of the supporting plate 21 in the width direction.

According to various embodiments of the present disclosure, as illustrated in FIG. 8, the second driving mechanism

72 can comprise a plurality of cylinders which are equidistantly distributed in the length direction of the supporting plate 21. As a result, the driving force of the second driving mechanism 72 applied to the outer end portion of the supporting plate 21 can be uniformly distributed in the length direction of the supporting plate 21. Thus, the fixing force applied to the substrate 3 can be uniformly distributed along the side of the substrate mounting area 6A, thereby ensuring the sealing contact between the substrate 3 and the substrate mounting plate 6 at different positions.

As illustrated in FIGS. 1 and 5, the plating apparatus further comprises a substrate stopper 61 which is configured to move from the outer side of the opening 15 to the middle part of the opening 15.

According to various embodiments of the present disclosure, as illustrated in FIG. 1, the substrate stopper 61 comprises a supporting stand 62 connected to the substrate mounting plate 6 and an arm 63 roughly parallel to the substrate mounting plate 6. An articulating member can be disposed at one end of the arm 63 and engage with a receiving hole in the supporting stand 62, so as to define an articulating axis of the arm 63. The articulating axis is perpendicular to the substrate mounting plate 6. A stop portion 63a can be connected to one end of the arm 63 and is, for instance, formed into a thin piece parallel to the substrate mounting plate 6. Thus, the arm 63 can rotate about the articulating axis between an idle position at the outer side of the opening 15 and a stop position above the opening 15 in the plane parallel to the substrate mounting plate 6. In some examples, an adjusting device (not illustrated), for instance, an adjusting bolt, of the stop portion 63a can be disposed on the arm 63 at one end of the stop portion 63a and is configured to adjust the distance between the stop portion 63a and the substrate mounting plate 6. Thus, the stop portion 63a can be adjusted to a position away from the substrate mounting plate 6 in the rotation process of the arm 63, thereby avoiding the collision with other units, for instance, the fixing device 2, on the substrate mounting plate 6.

Before plating treatment, the substrate stopper 61 can be disposed at the idle position (as illustrated in FIG. 5). In this case, the stop portion 63a is positioned on the outer side of the opening 15 of the side wall 5, so that the substrate 3 can be mounted and fixed on the substrate mounting plate 6.

During plating treatment, the arm 63 can be rotated to the stop position (as illustrated in FIG. 1). In this case, the stop portion 63a is positioned in the middle part of the opening 15 of the side wall 5 and blocks at the outer side of the substrate 3 to prevent the deformation of the substrate 3 under the pressure of the plating solution L in the tank body 1.

In some examples, as illustrated in FIGS. 10 to 12, the plating apparatus further comprises at least one sealing element. The sealing element can be disposed at an area of the substrate mounting plate 6 around the hole 65, so as to ensure a good sealing between the substrate 3 and the substrate mounting plate 6. The sealing element can further be disposed at an area of the side wall 5 around the opening 15, so as to ensure a good sealing between the side wall 5 and the substrate mounting plate 6.

In various embodiments of the present disclosure, as illustrated in FIG. 10, the sealing element is the form of a seal ring 64. The substrate mounting plate 6 can be provided with a recessed portion 68 (shown in FIG. 22) for accommodating the seal ring 64. In some examples, as illustrated in FIG. 10, the recessed portion 68 is open towards the outer side of the substrate mounting plate, so as to ensure the good

sealing between the substrate 3 and the substrate mounting plate 6. In some examples (not illustrated), the recessed portion 68 is open towards the inner side of the substrate mounting plate, so as to ensure the good sealing between the side wall S and the substrate mounting plate 6. In some examples (not illustrated), the recessed portion 68 for accommodating the seal ring 64 can be disposed on the outer side of the side wall S, so as to ensure the good sealing between the side wall S and the substrate mounting plate 6. In another embodiment of the present disclosure (not illustrated), the seal ring is in the form of a gasket; the gasket can be of a rectangular shape provided with a hollow part. The shape and the size of the hollow part are, for instance, substantially consistent with those of the hole 65 of the substrate mounting plate 6 or the opening 15 of the side wall S. The gasket is placed between the substrate 3 and the substrate mounting plate 6 and/or between the substrate mounting plate 6 and the side wall S.

As illustrated in the partial schematic diagram FIG. 11, the position of the sealing element is set such that: when the supporting plate 21 is at the parallel position, the position of the clamping end 24 of the clamping plate 22 at which the pressure is applied to the substrate mounting plate 6 at least partially overlaps with the position of the sealing element along the z axis. Thus, the sealing effect of the sealing element can be improved due to the pressure applied to the sealing element, thereby preventing the leakage of the plating solution L in the plating process.

In order to further improve the sealing effect, as illustrated in FIG. 12, the clamping plate 22 of the clamping piece 20 of the fixing device 2 can comprise a plurality of clamping ends 24. Correspondingly, the sealing elements can be distributed at positions where the plurality of clamping ends 24 exert the pressure towards the substrate mounting plate 6. When the sealing element is in the form of the seal ring 64, a plurality of seal rings 64 can be disposed at different positions from the side of the hole 65. When the sealing element is in the form of the gasket, the plurality of clamping ends 24 can apply the pressure at different positions of the gasket from the side of the hole 65.

It should be noted that although the sealing element is in the form of the seal ring 64 in FIGS. 11 and 12, the present disclosure is not limited thereto. As described above, the sealing element can also adopt the form of the gasket. When the supporting plate 21 is at the parallel position, an orthographic projection of the position where the clamping end 24 of the supporting plate 22 exerts the pressure towards the substrate mounting plate 6 on the substrate mounting plate 6 falls within an orthographic projection of the gasket on the substrate mounting plate 6.

The plating apparatus further comprises a plating solution drive device 8 disposed in the tank body 1. As illustrated in FIG. 1, the plating solution drive device 8 is set to face the opening 15 on the side wall S and configured to drive the plating solution L to flow towards the opening 15. Thus, the plating solution L near the substrate 3 can be rapidly replenished, the parameters such as temperature, concentration, pH and the like of the plating solution L in the vicinity of the substrate 3 remains constant, and the chemical composition of the plating solution L is uniformly dispersed. Therefore, the coating deposited on the substrate 3 can be formed in a uniform thickness to improve the yield of plating treatment and reduce the production cost.

According to various embodiments of the present disclosure, as illustrated in FIG. 13, the plating solution drive device 8 comprises a connecting frame 81 and a plurality of blades 82 connected to the connecting frame 81, and the

plurality of blades 82 are, for instance, formed as mutually parallel grids. The connecting frame 81 and the plurality of blades 82 are arranged in a plane parallel to the side wall S provided with the opening 15 (as illustrated in FIG. 1). The connecting frame 81 can be connected to a drive device via a slide bar 83. The drive device can drive the connecting frame 81 and the plurality of blades 82 to move in a plane parallel to the side wall S, for instance, performing reciprocating movement along the horizontal direction or the vertical direction, thereby driving a flow of the plating solution L in the vicinity of the substrate 3.

According to another embodiment of the present disclosure, as illustrated in FIG. 14, the plating solution drive device 8 comprises a connecting frame 81 and a plurality of ducts 84 connected to the connecting frame 81. The plurality of ducts 84 are juxtaposed in the plane parallel to the side wall S provided with the opening 15. A plurality of nozzles (not illustrated) are disposed on each duct 84 in an equidistant manner, and are open towards the side walls S provided with the openings 15. Thus, the plurality of nozzles can be arranged in an array in the plane parallel to the side wall S provided with the opening 15. During the plating process, the plating solution L can flow in the duct 84 and be sprayed towards the substrate 3 disposed on the opening 15 of the side wall S through the nozzles. The connecting frame 81 can be connected to the drive device via the slide bar 83. The drive device can drive the connecting frame 81, the plurality of ducts 84, and the plurality of nozzles to move in the plane parallel to the side wall S, for instance, performing reciprocating movement along the horizontal direction or the vertical direction, so as to uniformly spray the plating solution L onto the surface to be plated of the substrate 3.

According to another embodiment of the present disclosure, the plating solution drive device 8 can comprise both a plurality of blades 82 and a plurality of ducts 84 provided with nozzles. In this configuration, the movement of the blades 82 and the spraying action of the nozzles can produce a collaborative effect to better drive the flow of the plating solution with a view to form a uniform coating.

In some examples, the distance between adjacent nozzles is in a range from 1 mm to 5 mm, e.g., 1.5 mm. The bore diameter of the nozzle is in a range from 0.5 mm to 1 mm, e.g., 0.8 mm.

In order to obtain a coating with more uniform thickness, the plating solution drive device 8 can be arranged as close as possible to the side wall S provided with the opening 15. For instance, the distance between the plating solution drive device 8 and the side wall can be in a range from 2 mm to 4 mm.

In some examples, the plating solution drive device 8 can be mounted to the side wall S provided with the opening 15. In the embodiment as illustrated in FIG. 15, holders 85 for the plating solution drive device 8 can be disposed on the inner side of the side wall S. The holder 85 is roughly perpendicular to the side wall S and protrudes towards the inside of the tank body 1. The holders 85 are arranged on both sides of the plating solution drive device 8. The holders 85 can be provided with a through hole, and the slide bar 83 of the plating solution drive device 8 can be inserted into and supported by the through hole. The holders 85 have the dual function of holding the plating solution drive device 8 and guiding the movement of the plating solution drive device 8. Due to this configuration, the movement process of the plating solution drive device 8 can be implemented in a more stable manner, and the distance from the plating solution drive device 8 to the substrate to be plated 3 can be accurately controlled.

The sealing element (such as the seal ring 64) described in FIGS. 10 to 12 may be contaminated by the plating solution. For example, electrolytes (such as copper sulfate) of the plating solution L may crystallize around the hole 65 of the substrate mounting plate 6 and contaminate the sealing element. If the contaminations are not removed, the sealing element would be damaged and the sealing effect of the sealing element would be impaired.

To prevent the plating solution L from contaminating the sealing element around the hole 65, the plating apparatus may further include a cleaning module 90 1 for cleaning the sealing element. In particular, the cleaning module 90 would not hinder mounting the substrate 3 to the substrate mounting plate 6 of the plating apparatus. In some examples, the cleaning module 90 may be removably coupled to the plating apparatus such that the cleaning module 90 can be coupled to the plating apparatus after removing the substrate 3 from the substrate mounting plate 6 and decoupled from the substrate mounting plate 6 after cleaning the sealing element. In some examples, the cleaning module 90 is movably coupled to the plating apparatus such that the cleaning module 90 can be moved towards the sealing element after removing the substrate 3 from the substrate mounting plate 6 and moved away from the sealing element after cleaning the sealing element.

FIG. 17 illustrates a perspective view of the cleaning module 90 of the plating apparatus in various embodiments of the present disclosure. The cleaning module 90 includes a roller assembly 92 for cleaning the sealing element, and a plate assembly 94 for providing a mechanical support to the roller assembly 92. The roller assembly 92 includes a feeder roller 922 for supplying a fresh tape 926 to the sealing element and a receiver roller 924 for receiving a contaminated tape 928. The feeder roller 922 and the receiver roller 924 can rotate around a feeder roller axis 923 and a receiver roller axis 925, respectively. The fresh tape 926 is a new, unused, or recovered tape that can be used for cleaning the sealing element; and the fresh tape 926 is then turned into the contaminated tape 928 after cleaning the sealing element. The contaminated tape 928 may be recovered back to the fresh tape 926 for recycling use of the contaminated tape 928.

The fresh tape 926 may be made of any materials which can absorb the plating solution L around the sealing element. In some examples, the fresh tape 926 comprises non-water proof fabrics, such as non-woven wipes which can efficiently absorb the plating solution L. The non-woven wipes may include a composite material of viscose, polyesters, cotton, nylon, microfibers and pulps. For example, the non-woven wipes may be made of woodpulp and polyester. Accordingly, the non-woven wipes have a soft nature and thus would not make damage to the sealing element during the cleaning. The non-woven wipe may further include spunlaced non-woven wipes or needle-punched non-woven wipes according to the chemical nature of the plating solution L.

In some examples, the roller assembly 92 may include one or more tension rollers 930 for creating an internal tension to the fresh tape 926 and/or the contaminated tape 928 for facilitating movement of the fresh tape 926 and/or the contaminated tape 928 in the roller assembly 92. As shown in FIG. 17, the tension roller 930 includes a second tension roller 9304 located adjacent to the receiver roller 924 for creating the internal tension to the contaminated tape 928. Alternatively, the tension roller 930 may include a first tension roller 9302 (shown in FIG. 22) located adjacent to the feeder roller 922 for creating the internal tension to the

fresh tape 926. Alternatively, the roller assembly 92 may have both the first tension roller 9302 and the second tension roller 9304.

In some examples, the roller assembly 92 may include one or more idle rollers 932 for directing the movement of the fresh tape 926 and/or the contaminated tape 928 in the roller assembly 92. As shown in FIG. 17, the idle roller 932 includes a second idle roller 9324 located adjacent to the receiver roller 924 for directing the contaminated tape 928 towards the receiver roller 924. Alternatively, the idle roller 932 includes a first idle roller 9322 (shown in FIG. 22) located adjacent to the feeder roller 922 for directing the fresh tape 926 away from the feeder roller 922 and towards the sealing element. Alternatively, the roller assembly 92 may have both the first idle roller 9322 and the second idle roller 9324. In some examples, the first idle roller 9322 may be in contact with the first tension rollers 9302 via the fresh tape 926 for facilitating the creation of the internal tension and meanwhile for providing a more compact profile for the roller assembly 92. Similarly, the second idle rollers 9324 may be in contact with the second tension roller 9304 via the contaminated tape 928 for the same advantages.

The plate assembly 94 may have a first side plate 942 and a second side plate 944 at two opposed sides of the roller assembly 92 for rotatably fix the feeder roller axis 923 and the receiver roller axis 925 such that the feeder roller 922 and the receiver roller 924 can rotate around the feeder roller axis 923 and the receiver roller axis 925 to supply the fresh tape 926 and receive the contaminated tape 928, respectively. The plate assembly 94 may include a base plate 946 connecting the first side plate 942 and the second side plate 944 for enclosing the roller assembly 92 at a rear side. The plate assembly 94 may also include a connecting bar 948 connecting the first side plate 942 and the second side plate 944 at a front side opposed to the base plate 946 at the rear side. The connecting bar 948 is located between the feeder roller 922 and the receiver roller 924 for not blocking or interfering rotation of the feeder roller 922 and the receiver roller 924.

In some examples, the cleaning module 90 may include a cushion 96 attached to the base plate 946 and opposed to the roller assembly 92. The cushion 96 has a front surface 962 (shown in FIG. 22) in contact with the base plate 946 and a rear surface 964 opposed to the front surface 962. During the cleaning with the cleaning module 90, the rear surface 964 would be in close contact with the fresh tape 926 and the contaminated tape 928 which are further pressed against the sealing element accommodated in the substrate mounting plate 6.

The cushion 96 may be in a sheet configuration and made of soft materials for mitigating the pressure applied between the fresh tape 926 and the contaminated tape 928 against the sealing element accommodated in the substrate mounting plate 6. In some examples, the soft materials may include silicone rubbers composed of silicone polymers which typically contains silicon together with carbon, hydrogen, and oxygen. Other similar soft materials may also be used, such as silicone foams or rubber sponges.

FIG. 18 illustrates a perspective view of the roller assembly 94 in FIG. 17 at a waiting location 902 (shown in a dashed square in FIG. 18) away from the sealing element accommodated in the substrate mounting plate 6 for not blocking or interfering mounting the substrate 3 onto the substrate mounting plate 6.

The cleaning module 90 may include a holding station 99 configured to hold the roller assembly 92 at the waiting configuration 902 when the substrate 3 is mounted onto the

substrate mounting plate 6 for the plating treatment; and then configured to release the roller assembly 92 for cleaning the sealing element when the substrate 3 is removed after the plating treatment. As shown in FIG. 18, the holding station 99 is located above (in a X-direction of a Cartesian coordinate system shown in FIG. 18) the substrate mounting plate 6. It is understood that the holding station 99 may be located at other locations away from the substrate mounting plate 6, such as below (in the X-direction of the Cartesian coordinate system) the substrate mounting plate 6, on a left side or on a right side (in a Y-direction of the Cartesian coordinate system) of the substrate mounting plate 6, or anywhere appropriate for the waiting location 902.

Accordingly, the cleaning module 90 may include a handling assembly 98 for moving the roller assembly 92 from the holding station 99 at the waiting location 902 towards a working location 904 (shown in the dashed square in FIG. 18) adjacent to the substrate mounting plate 6 before cleaning the sealing element and then for moving the roller assembly 92 back to the holding station 99 after cleaning the sealing element. The handling assembly 98 may include a first guiding rail 982 for moving the roller assembly 92 upwardly and downwardly in the X-direction of the Cartesian coordinate system and a second guiding rail 986 for moving the roller assembly 92 inwardly and outwardly in a Z-direction of the Cartesian coordinate system such that the roller assembly 92 can be moved accurately to the working location 904. In some examples, the X-direction is parallel to an edge of the opening 15 of the side wall S of the tank body 1; and the Z-direction is perpendicular to a plane containing or parallel to the side wall S of the tank body 1. In some examples, the handling assembly 98 has a handle 984 configured to grasp the roller assembly 92 and to move the roller assembly 92 along the first guiding rail 982 and the second guiding rail 986.

The roller assembly 92 may have either a larger profile or a smaller profile in relation to the sealing element. For example, if the roller assembly 92 has both a length and a width larger than the sealing element in the X-direction and the Y-direction, the roller assembly 92 can clean the sealing element without movement. If the sealing element cannot be completely covered by the roller assembly 92 by the length or the width of the roller assembly 92, the roller assembly 92 needs to move in the X-direction or the Y-direction during the cleaning in order to clean all parts of the sealing element.

As shown in FIG. 18, the first guiding rail 982 further has two first guiding rail members 9822, 9824 extending in a parallel configuration in the X-direction and at two opposed sides of the roller assembly 92 in the Y-direction; and the handle 984 is slidably coupled to the two first guiding rail members 9822, 9824. The parallel configuration enables the handle to traverse along the two first guiding rail members 9822, 9824. The handle 984 can be actuated by a first linear actuator 983 to slide along the two first guiding rail members 9822, 9824 in the X-direction. The second guiding rail 986 also has two second guiding rail members 9862, 9864 in a parallel configuration in the Z-direction and at two opposed sides of the roller assembly 92 in the Y-direction. The parallel configuration enables the handle to traverse along the two second guiding rail members 9862, 9864. The two second guiding rail members 9862, 9864 are slidably coupled with the handle 984 together to the two first guiding rail members 9822, 9824 respectively, such that the two second guiding rail members 9862, 9864 can move together with the handle 984 in the X-direction. When the handle 984 and the two second guiding rail members 9862, 9864 are moved directly over the working location 904 in the Z-di-

rection, the handle 984 is actuated by a second linear actuator 987 to move along the two second guiding rail members 9862, 9864 in the Z-direction to finally arrive at the working location 904. Two grippers 988 may be used to grasp the roller assembly 92 such that the roller assembly 92 is accurately moved together with the handle 984 to arrive at the working location 904 for cleaning the sealing element.

Alternatively, the roller assembly 92 and the handle 984 may be accurately installed at the working location 904 after the substrate 3 is removed from the substrate mounting plate 6 before cleaning the sealing element and then removed from the working location 904 after cleaning the sealing element. Therefore, it is not necessary to define the waiting location 902; accordingly, the holding station 99 and the handling assembly 98 are not needed to move the roller assembly 92 to the working location 904 for the cleaning module 90.

FIG. 19 illustrates a perspective view of the roller assembly 92 held at the holding station 99 at the waiting position 902 in FIG. 18. The holding station 99 includes a securing mechanism 992 for removably securing the roller assembly 92 at the holding station 99 and a support plate 994 for coupling the securing mechanism 992 to the plating apparatus.

In some examples, the securing mechanism 992 includes a cylinder 996 coupled to the support plate 994 and a locker 998 coupled to the cylinder 996 for securing the roller assembly 92. The locker 998 may have two protrusions 9982, 9984; while the each of the first side plate 942 and the second side plate 944 may have two receiving holes (i.e., first receiving holes 9422, 9424 for the first side plate 942 and second receiving holes 9442, 9444 for the second side plate 944) accordingly for receiving the two protrusions 9982, 9984. Since the protrusions 9982, 9984 can be inserted and removed from the two receiving holes 9422, 9424 of the first side plate 942 and the two receiving holes 9442, 9444 of the second side plate 944 respectively, the holding station 99 can secure and release the roller assembly 92 repetitively. The locker 998 may be activated by the cylinder 996 to lock the roller assembly 92. For example, the cylinder 996 may have a telescoping end 9962 which can extend outside and push the locker 998 towards the side plates 942, 944 of the plate assembly 94 after getting in contact with the locker 998. The locker 998 may have a locker cavity 9986 corresponding to the telescoping end 9962. Accordingly, the telescoping end 9962 extends outside, then arrives at the locker cavity 9986, and finally pushes the locker 998 to move towards the side plates 942, 944 until the two protrusions 9982, 9984 are inserted into the two first receiving holes 9422, 9424 of the first side plate 942, respectively.

FIG. 20 illustrates an enlarged view of the securing mechanism 992 securing the roller assembly 92 at the holding station 99 in FIG. 19. It is clearly shown that the two protrusions 9982, 9984 can be inserted into and removed from the two first receiving holes 9422, 9424 of the first side plate 942. It is understood that the securing mechanism 992 shown in FIG. 19 and FIG. 20 are exemplary only and may have other designs which also fall into the disclosure of the present invention.

FIG. 21 illustrates a perspective view of the roller assembly 92 of the cleaning module 90 in FIG. 17 at the working location 904. The substrate 3 (not shown) is removed from the substrate mounting plate 6 and thus the sealing element (such as the seal ring 64) is exposed for cleaning. The roller assembly 92 is released from the holding station 99 and then moved from the waiting location 902 to the working location 904 via the first guiding rail 982 in the X-direction and the

second guiding 986 in the Z-direction. If the length of the roller assembly 92 is larger than the sealing element in X-direction, the roller assembly 92 can completely cover the sealing element for cleaning the sealing element without movement in the X-direction. Alternatively, the roller assembly 92 has a smaller length than the sealing element such that the roller assembly 92 can clean only a portion of the sealing element in the X-direction each time. As a result, the roller assembly 92 needs to move for several times along the first guiding rail 982 in the X-direction to clean all portions of the sealing element.

Similarly, if the width of the roller assembly 92 is smaller than the sealing element, the roller assembly 92 can clean only a portion of the sealing element in the Y-direction each time; and the roller assembly 92 needs to move for several times in the Y-direction to clean all portions of the sealing element. In some examples, the two grippers 988 may be movable along the handle 984 in order to move the roller assembly 92 in the Y-direction. Alternatively, the two first guiding rail members 9822, 9824 may be movable in the Y-direction in order to move the roller assembly 92 in the Y-direction if the grippers 988 are fixed at the handle 984.

FIG. 22 illustrates a cross-sectional view of the cleaning module 90 for cleaning the sealing element (represented by the seal ring 64 in FIG. 22) of the plating apparatus. The fresh tape 926 is prepared in a roll configuration and installed at the feeder roller 922 before the cleaning. Accordingly, the fresh tape 926 is supplied from the feeder roller 922, applied with the internal tension by the first tension roller 9302, and then directed by the first idle roller 9322 to the seal ring 64. The fresh tape 926 cleans the seal ring 64 and is turned into the contaminated tape 928 accordingly. The contaminated tape 928 is then applied with the internal tension at the second tension roller 9304 and directed by the second idle roller 9324 to the receiver roller 924. The contaminated tape 928 is received by and temporarily stored at the receiver roller 924 in a roll configuration. The contaminated tape 928 may be recovered back (such as by washing) to the fresh tape 926 for recycling usage.

In FIG. 22, it is clearly shown that the seal ring 64 is accommodated in the recessed portion 68 of the substrate mounting plate 6. The fresh tape 926 and the contaminated tape 928 are sandwiched between the base plate 946 and the substrate mounting plate 6 for cleaning the sealing element. To protect the fresh tape 926 and the contaminated tape 928 from being damaged by the base plate 946, the cushion 96 is positioned between the base plate 946 and the fresh tape 926 and the contaminated tape 928. It is also shown that the first tension roller 9302 is in close contact with the first idle roller 9322 via the fresh tape 926; while the second tension roller 9304 is also in close contact with the second idle roller 9324 via the contaminated tape 928. In other words, the fresh tape 926 is sandwiched between the first tension roller 9302 and the first idle roller 9322; and the contaminated tape 928 is also sandwiched between the second tension roller 9304 and the second idle roller 9324. In this way, the internal tension can be easily applied to the fresh tape 926 and the contaminated tape 928 without damage.

The operation method of the plating apparatus will be described below and is used for performing plating treatment on the substrate to be plated 3.

Firstly, placing the substrate 3 on the outer side of the side wall and at the position of the opening, and operating the fixing device 20 to fix the substrate 3.

In some examples, the plating apparatus comprises a substrate mounting plate 6 fixed to the outer side of the side wall, the substrate mounting plate 6 comprises a hole 65 and

a substrate mounting area 6A arranged around the hole 65, and the position of the hole 65 corresponds to the position of the opening. In this case, the step of operating the fixing device 20 to fix the substrate 3 further comprises: operating the fixing device 20 to fix the substrate 3 to the substrate mounting plate 6.

In some examples, the substrate mounting area 6A is provided with electrical contacts 66 configured to be electrically connected with the substrate 3, and the plating apparatus further comprises a resistance measuring device electrically connected to the electrical contacts 66. In this case, the step of operating the fixing device 20 to fix the substrate 3 further comprises: using the resistance measuring device to measure the contact resistance between the substrate 3 and the electrical contacts 66, and determining the connection status of the substrate 3 and the electrical contacts 66.

Secondly, performing plating treatment on the substrate 3.

In some examples, performing plating treatment on the substrate 3 can comprise: injecting the plating solution into the tank body 1, so that the plating solution can contact at least a part of the substrate 3, and applying a cathode voltage to the substrate 3 through the electrical contacts 66, applying an anode voltage to the anode of the plating apparatus, and then performing plating treatment on the substrate 3.

In some examples, the plating apparatus comprises a plating solution drive device 8 being disposed in the tank body 1 and facing the opening, and the plating solution drive device 8 is configured to drive the plating solution to flow towards the opening. In this case, the step of performing plating treatment on the substrate 3 can comprise: using the plating solution drive device 8 to drive the plating solution to flow towards the substrate 3.

FIG. 16 illustrates an operation method of the plating apparatus provided by various embodiments of the present disclosure. The method comprises:

S1: placing the substrate 3 on the outer side of the side wall S and at the position of the opening 15; and

S2: operating the fixing device 2 to fix the substrate 3 on the substrate mounting plate 6.

For instance, the first driving mechanism 71 is operated at first so that the clamping plate 22 can move from the retraction position to the extension position and the clamping end 24 of the clamping plate 22 can move to the position above the substrate mounting area 6A, and then the second driving mechanism 72 is operated so that the supporting plate 21 can rotate from the inclination position to the parallel position and the clamping end 24 of the clamping plate 22 can apply a pressure to the substrate 3 in the substrate mounting area 6A.

S3: utilizing the resistance measuring device to detect the connection status between the substrate 3 and the substrate mounting plate 6.

S4: turning on a plating solution pumping device 8 to inject the plating solution L into the tank body 1 and allow the plating solution L to contact at least a part of the substrate 3.

S5: turning on the power supply device 5 to apply a voltage between the substrate to be plated 3 and the anode 4.

S6: turning on the plating solution drive device 8 to perform a reciprocating motion in the plane parallel to the substrate 3, and drive the plating solution L to flow towards the surface to be plated of the substrate 3.

S7: performing the plating process and timing the plating process.

S8: turning off the power supply device 5.

S9: turning off the plating solution pumping device, and stopping injecting the plating solution into the tank body 1.

S10: turning off the plating solution drive device 8.

S11: discharging the plating solution from the tank body 5 1.

S12: operating the fixing device 2 to unfix the substrate 3 from the substrate mounting area 6A and detach the substrate 3 from the substrate mounting plate 6.

FIG. 23 illustrates a schematic diagram of cleaning the sealing element of the plating apparatus following S12 of the 10 operation method of the plating apparatus in FIG. 16. The cleaning method comprises:

S13: positioning the roller assembly 92 to the working 15 location 904. If the roller assembly 92 is held by the holding station 99 at the waiting location 902, a pre-step is needed before S13 to lease the roller assembly 92 from the holding station 99. Alternatively, if the roller assembly 92 is placed apart from the cleaning module 90, another pre-step is needed before S13 for 20 accurately installing the roller assembly 92 to the cleaning module 90 at the working location 904.

S14: supplying the fresh tape 926 from the feeder roller 25 922.

S15: creating the internal tension to the fresh tape 926 by 25 the first tension roller 9302.

S16: directing the fresh tape 926 to the sealing element 30 accommodated in the substrate mounting plate 6 by the first idle roller 9322.

S17: cleaning the sealing element with the fresh tape 926; and the fresh tape 926 is turned into the contaminated tape 928 accordingly.

S18: creating the internal tension to the contaminated tape 35 928 by the second tension roller 9304.

S19: directing the contaminated tape 928 to the receiver 40 roller 924 by the second idle roller 9324.

S20: receiving the contaminated tape 928 into the receiver 45 roller 924.

S21: positioning the roller assembly 92 away from the working location 904. If the cleaning module 90 includes the holding station 99 at the waiting location 902, the roller assembly 92 is moved to the waiting location 902. If the cleaning module 90 does not include the holding station 99, the roller assembly 92 is removed from the cleaning module 90.

Further features of the present disclosure may be found in the claims, the drawings, and the description of the drawings. The features and combinations of features mentioned above in the description and the features and combinations of features which are further illustrated in the drawings and/or independently illustrated in the drawings are not only used for the respectively indicated combinations, but also for other combinations or for individual use, without departing from the scope of the present disclosure. The details of the present disclosure, which are not explicitly illustrated and explained in the drawings but are presented from the detailed description of the features through independent feature combinations are thus comprised and disclosed. Therefore, details and combinations of features that do not have all of the features of the originally formed independent claims should also be considered as disclosed.

The invention claimed is:

1. A plating apparatus for performing plating treatment on a substrate, comprising:
a tank body comprising at least one side wall, the at least one side wall being provided with an opening extend-

ing from an inside to an outside of the tank body, the tank body being configured to accommodate a plating solution;

a fixing device configured to fix the substrate to the outside of the tank body at the opening of the at least one side wall;

at least one sealing element disposed around the opening; and

a cleaning module coupled to the plating apparatus for cleaning the at least one sealing element, wherein the cleaning module comprises a plate assembly and a roller assembly coupled together, wherein the plate assembly provides a mechanical support to the roller assembly and the roller assembly is configured to clean the at least one sealing element, and

wherein the roller assembly comprises a feeder roller for supplying a fresh tape to the at least one sealing element and a receiver roller for receiving a contaminated tape from the at least one sealing element, wherein the fresh tape is turned into the contaminated tape for cleaning the at least one sealing element.

2. The plating apparatus according to claim 1, wherein the roller assembly further comprises a tension roller either before or after the at least one sealing element for creating an internal tension to the fresh tape or the contaminated tape moving in the roller assembly.

3. The plating apparatus according to claim 2, wherein the roller assembly further comprises a first idle roller after the feeder roller for directing the fresh tape from the feeder roller to the at least one sealing element and a second idle roller after the at least one sealing element for directing the contaminated tape from the at least one sealing element to the receiver roller.

4. The plating apparatus according to claim 1, wherein the plate assembly comprises two side plates and a base plate connecting the two side plates, wherein the feeder roller and the receiver roller are configured to be rotatably coupled to the two side plates.

5. The plating apparatus according to claim 1, wherein the cleaning module further comprises a handling assembly for moving the roller assembly towards a working location where the roller assembly is configured to clean the at least one sealing element and for moving the roller assembly away from the working location after cleaning the at least one sealing element.

6. The plating apparatus according to claim 5, wherein the handling assembly comprises a first guiding rail extending in a first direction substantially parallel with an edge of the opening of the at least one side wall and a handle movably coupled to the first guiding rail for moving the roller assembly along the first guiding rail in the first direction.

7. The plating apparatus according to claim 6, wherein the handling mechanism further comprises a second guiding rail extending in a second direction substantially perpendicular to a plane of a substrate mounting plate coupled to the at least one side wall, and the handle is movably coupled to the second guiding rail for moving the roller assembly along the second guiding rail in the second direction.

8. The plating apparatus according to claim 7, wherein the cleaning module further comprises a first linear actuator and a second linear actuator for driving the roller assembly to move along the first guiding rail and the second guiding rail, respectively.

9. The plating apparatus according to claim 5, wherein the cleaning module comprises a holding station for holding the roller assembly at a waiting location away from the working

31

location, and the holding station comprises a securing mechanism for removably securing the roller assembly at the holding station.

10. The plating apparatus according to claim 9, wherein the securing mechanism comprises a cylinder coupled to the plating apparatus and a locker coupled to the cylinder for removably locking the roller assembly at the holding station, wherein the locker is activated by the cylinder to lock the roller assembly.

11. A cleaning module for cleaning at least one sealing element of a plating apparatus, comprising:

a plate assembly coupled to the plating apparatus; and a roller assembly coupled to the plate assembly for cleaning the at least one sealing element at a working location, wherein the roller assembly is configured to supply a fresh tape to the at least one sealing element and configured to receive a contaminated tape from the at least one sealing element, wherein the fresh tape is turned into the contaminated tape for cleaning the at least one sealing element.

12. The cleaning module according to claim 11, wherein the roller assembly comprises a feeder roller for supplying the fresh tape to the at least one sealing element and a receiver roller for receiving the contaminated tape.

13. The cleaning module according to claim 11, further comprising:

a holding station for holding the roller assembly at a waiting location away from the working location; and a handling assembly for moving the roller assembly towards the working location.

14. The cleaning module according to claim 11, wherein the cleaning module is configured to be attached to the plating apparatus at the working location and configured to be detached from the plating apparatus after cleaning the at least one sealing element.

15. A cleaning method for cleaning the at least one sealing element of the plating apparatus with the cleaning module according to claim 13, comprising:

positioning the roller assembly of the cleaning module at the working location; cleaning the at least one sealing element with the fresh tape provided from the roller assembly; and positioning the roller assembly away from the working location.

16. The cleaning method according to claim 15, wherein the providing the fresh tape further comprises:

supplying the fresh tape from a feeder roller of the roller assembly; directing the fresh tape to the at least one sealing element by a first idle roller of the roller assembly; directing the contaminated tape to a receiver roller after the at least one sealing element by a second idle roller of the roller assembly; and receiving the contaminated tape into the receiver roller of the roller assembly.

17. The cleaning method according to claim 16, wherein the providing the fresh tape further comprises:

creating a first internal tension to the fresh tape by a first tension roller located after the feeder roller and before the at least one sealing element; and creating a second internal tension to the contaminated tape with a second tension roller located after the at least one sealing element and before the receiver roller.

18. The cleaning method according to claim 15, wherein the positioning the roller assembly of the cleaning module at the working location comprises: moving the roller assembly from a waiting location to the working location along a first

32

guiding rail and a second guiding rail, wherein the first guiding rail is substantially perpendicular to the second guiding rail.

19. A plating apparatus for performing plating treatment on a substrate, comprising:

a tank body comprising at least one side wall, the at least one side wall being provided with an opening extending from an inside to an outside of the tank body, the tank body being configured to accommodate a plating solution;

a fixing device configured to fix the substrate to the outside of the tank body at the opening of the at least one side wall;

at least one sealing element disposed around the opening; and

a cleaning module coupled to the plating apparatus for cleaning the at least one sealing element, wherein the cleaning module comprises a plate assembly and a roller assembly coupled together, wherein the plate assembly provides a mechanical support to the roller assembly and the roller assembly is configured to clean the at least one sealing element,

wherein the cleaning module further comprises a handling assembly for moving the roller assembly towards a working location where the roller assembly is configured to clean the at least one sealing element and for moving the roller assembly away from the working location after cleaning the at least one sealing element, and

wherein the handling assembly comprises a first guiding rail extending in a first direction substantially parallel with an edge of the opening of the at least one side wall and a handle movably coupled to the first guiding rail for moving the roller assembly along the first guiding rail in the first direction.

20. A plating apparatus for performing plating treatment on a substrate, comprising:

a tank body comprising at least one side wall, the at least one side wall being provided with an opening extending from an inside to an outside of the tank body, the tank body being configured to accommodate a plating solution;

a fixing device configured to fix the substrate to the outside of the tank body at the opening of the at least one side wall;

at least one sealing element disposed around the opening; and

a cleaning module coupled to the plating apparatus for cleaning the at least one sealing element, wherein the cleaning module comprises a plate assembly and a roller assembly coupled together, wherein the plate assembly provides a mechanical support to the roller assembly and the roller assembly is configured to clean the at least one sealing element,

wherein the cleaning module further comprises a handling assembly for moving the roller assembly towards a working location where the roller assembly is configured to clean the at least one sealing element and for moving the roller assembly away from the working location after cleaning the at least one sealing element, and

wherein the cleaning module comprises a holding station for holding the roller assembly at a waiting location away from the working location, and the holding sta-

tion comprises a securing mechanism for removably securing the roller assembly at the holding station.
